UNITED STATES PATENT OFFICE.

HOWARD E. REACH, OF LOS ANGELES, CALIFORNIA, ASSIGNOR TO THOMAS R. BARRABEE, OF LOS ANGELES, CALIFORNIA.

TALKING-MACHINE

1,384,347.

Specification of Letters Patent. Patented July 12, 1921.

Application filed December 27, 1919. Serial No. 347,862.

To all whom it may concern:

Be it known that I, HOWARD E. REACH, a citizen of the United States, residing at Los Angeles, county of Los Angeles, and 5 State of California, have invented a certain new and useful Improvement in Talking-Machines, of which the following is a specification.

The present invention relates to a means 10 for engaging the turntable of a talking machine to stop rotation thereof and it has especial reference to a means actuatable by the tone arm for automatically braking the turntable.

15 The prime object of the invention is to provide a graphophone in which the tendency of travel of the tone arm is always toward the center of the record, irrespective of the sound grooves and to utilize the 20 gravitational force of the tone arm for actuating the brake for the turntable.

One of the chief obstacles at present encountered in the successful operation of the 25 brake by the tone arm, is the lack of force or power of the tone arm to actuate the braking mechanism at the completion of the record and this is due primarily to the fact that the propelling means for the tone arm is the spiral sound grooves of the record, 30 which are shallow and insufficient to overcome any but an excessively feeble resistance offered by a brake.

Where even an additional groove of 35 smaller spirality and greater depth is provided in the record as a continuation of the spiral sound grooves to cause a sudden acceleration of the travel of the tone arm, it very frequently happens that the stylus, worn down by the rotating disk, remains in 40 the last groove of the record and fails to follow the terminal groove for causing the tone arm to actuate the brake.

Therefore it is a main object of this invention to impart to the tone arm a constant 45 tendency to gravitate or incline toward the center of the disk, without impairing the normal travel of the stylus in the sound undulations, and thereby to prevent the stylus from continuing in a circular groove that 50 may be imperfectly formed.

The objects herein mentioned and others 55 hereinafter appearing are accomplished by the means shown in the accompanying drawings, which illustrate a preferred form of embodiment of the invention, and in which,

Figure 1 is a perspective view of a talking machine showing a disk, turntable, brake for the turntable and the tone arm, and

Fig. 2 is a fragmentary view of a tone arm showing its manner of mounting.

The invention consists essentially in so disposing the tone arm with respect to the disk and its supporting turntable that to it is imparted a tendency to gravitate to the center, whether the stylus of the sound box 65 is in engagement with the grooves of the record or free of them, and such disposition may be effected by tilting the tone arm 1, as by inserting between the tone arm swivel or support 2 and the top of the cabinet 3, 70 a tapering or wedge shaped washer or member 4 that will incline the tone arm swivel or support at an angle to the horizontal, the degree of such inclination being gaged according to the amount of gravitational 75 force desired.

On the tone arm 1 may be a lever 5, in the path of travel of which is the trigger 6 of a braking mechanism, of any approved design, such as shown, and consisting for 80 instance of a tubular body 7, fastened on the cabinet 3, and containing a spring actuated plunger 8, in which the trigger is mounted. The tubular body 7 is provided with a longitudinal slot 9, communicating 85 with a slot 10, at right angles thereto, for retaining the trigger 6 in position prior to actuation thereof by the lever 5.

In order more effectually to insure the acceleration of the tone arm 1, an additional 90 groove 10' may be provided in the record, but due to the increased force of the tone arm by reason of the inclination thereof as explained, this provision is not necessary, since the inclination of the tone arm is sufficient 95 to cause the stylus to leave the last groove of the record and the tone arm to gravitate to the center, whereupon the actuation of the brake will occur.

Obviously any means for tilting or disposing the tone arm at an angle to the horizontal may be employed, and hence other forms, arrangements or contrivances may be adopted for causing a gravitational inclination toward the center of the record disk.

What I claim, is:—

1. In a phonograph, the combination of a support having a pivotal axis for the tone arm tilted to the vertical, a tone arm swiveled on said support so it will tend to gravi- 110

tate toward the center of the turntable, and a brake mechanism actuatable by the tone arm at a selected point in its movement.

2. In a phonograph, the combination of a support having a pivotal axis for a tone arm, 5 means to tilt said support so that said axis will be at an angle to the vertical, a tone arm

pivotaly associated with said support so that it will tend to gravitate toward the center of the turntable, and a braking mechanism actuated by said tone arm at a selected point in its movement. 10

In testimony whereof I have set my hand.

HOWARD E. REACH.
